UNITED STATES PATENT OFFICE.

WALTER RACHALS, OF BOARDMAN, OHIO.

SHEARING-MACHINE.

1,298,783.

Specification of Letters Patent.

Patented Apr. 1, 1919.

Application filed April 18, 1916. Serial No. 91,948.

To all whom it may concern:

Be it known that I, WALTER RACHALS, a citizen of the United States, residing at Boardman, in the county of Mahoning and 5 State of Ohio, have invented certain new and useful Improvements in Shearing-Machines, of which the following is a specification.

This invention relates to shearing devices, 10 and more particularly to a machine for shearing heavy stock materials in foundries and mills.

Primarily, the present invention has in view a machine of the character set forth 15 capable of imposing a powerful leverage on the shearing instrumentalities by means of a novel arrangement of levers whereby the cutting capacity of the shearing means represents a maximum multiple of the power 20 used in effecting the operation of the device.

Another object of the invention is to provide a simple and substantial arrangement of parts which are strong and reliable in operation, and furthermore provide for the 25 observation of the working of the knife blocks during the operation of the machine, thus facilitating the handling of the material to be sheared.

With the above and other objects in view 30 which will more readily appear as the nature of the invention is better understood, the same consists in the novel construction, combination and arrangement of parts hereinafter more fully described, illustrated and claimed.

A preferred and practical embodiment of 35 the invention is illustrated in the accompanying drawings, in which—

Figure 1 is a side elevation of the improved shearing machine.

Fig. 2 is a vertical sectional view showing 40 the position of the operating parts when the knife blocks are separated.

Fig. 3 is a view similar to Fig. 2 showing 45 the position of the operating parts when the knife blocks are substantially in shearing position.

Fig. 4 is a vertical cross sectional view 50 on the line 4—4 of Fig. 1 looking in the directions of the arrows.

Similar reference characters designate 55 corresponding parts throughout the several figures of the drawings.

In carrying out the present invention, it 55 is proposed to provide a machine frame designated generally as F, and which may include in its organization strong and substantial casting sections whose dimensions and proportions are determined by the requirements of the machine. In this connection, it will be observed that the frame comprises a bed section 1, including a stationary knife block 2, and an upper supporting 60 and housing section H.

As will be observed from the several figures of the drawings, the stationary knife block 2 is preferably provided with a knife receiving recess 3 for receiving the ledger blade 4 of the shear, and coöperates with a reciprocating knife block 5. One end 6 of this block is slidably guided in the vertically disposed guideway 7 of the framework of the machine, while the opposite end 8 thereof slides on a guidepost 9 at the front end 65 of the machine. Thus, the reciprocating knife block 5 is adapted to have a free reciprocating movement in a vertical direction, and to fully coöperate with the lower knife block 2, the same is provided with a 70 knife receiving recess 10 and a suitable cutting or shearing blade 11.

For the purpose of imparting the necessary downward shearing movement to the knife block 5, the same has preferably connected to its upper face, the lower ends of the actuating plungers 12 and 13, the upper ends of which are respectively pivotally engaged with the working ends of a main lever 14 and supplementary lever 15. That is 85 to say, the upper ends of the plungers 12 and 13 loosely engage in the socketed working ends of the said main and supplementary levers. These actuating plungers are of a substantial and wide formation, the 90 same being preferably coextensive with the width of the knife block 5 as will be observed from Fig. 4 to evenly distribute the shearing power over the entire knife block.

The main lever 14 is pivotally supported 100 as at 16 in the opposite walls of the housing H, and is of substantially triangular formation. This type of main operating lever makes possible the use of a link 17 for connecting the same with the upper end of 105 the supplementary operating lever 15 which is journaled as at 18 in the housing of the framework a short distance to one side of

the journal bearing 16 of the main lever. The end of the main lever 14 opposite its connection with the plunger member 12 is connected with a suitable link 19 which in 5 turn is pivotally connected with a crank arm 20 rigidly carried by a power shaft 21 journaled in the bed portion of the frame. Power to the shaft 21 may be supplied from 10 any convenient source, and when rotating 10 in the direction of the arrow in Figs. 2 and 3 imparts a rocking motion to the main operating lever 14 which with the aid of the supplementary lever 15 imparts a true vertical reciprocating motion to the upper 15 knife block.

In order to transmit the full leverage effect from the main lever 14 to the reciprocating block 5, it will be observed that the axes 16 and 18 of the main and the supplemental lever are arranged in relatively close proximity and in the same horizontal plane, while the plungers or connectors 12 and 13 are duplicates in position and length as well as having the upper ends thereof engaging 25 with their respective levers at the same distance from the center of the axes of said levers. This specific combination and arrangement of parts has been found very effective to secure the maximum leverage 30 effect contemplated by the present invention.

Furthermore, it will be observed that the main lever 14 lies in a substantially horizontal plane, and has a vertical swinging movement, while the supplementary lever 15 is substantially upright and swings in a horizontal plane. In other words, the swinging movement of the power ends of the levers 14 and 15 are substantially at right 35 angles to each other, while the work ends thereof have a relatively short reciprocating movement in substantially vertical planes which are parallel to each other.

In order to facilitate the operation and 40 increase the efficiency of the machine it is preferred to balance or offset the weight of the reciprocating knife block 5, and to this end, there is employed a suitable counterbalance device designated generally as B, 45 which operates in a pit in the floor on which the machine rests. This device essentially comprises the vertical supporting standards 22 adapted to freely slide through guide openings in the stationary knife block 2 at 50 each side of the shearing blades 4 and 11. The upper ends of these rods are rigidly connected as at 23 with the upper knife block, while the lower ends 24 thereof are rigidly secured in a suitable yoke 25 which 55 is constructed to pivotally receive one end 26 of a weighted lever 27. This weighted lever 27, as will be observed from Fig. 4 is fulcrumed as at 28 in a suitable link 29 suspended from the stationary knife block 60 2. Thus, the upper knife block is fully 65

counterbalanced or lifted by the device B, and remains inert unless acted upon by the system of levers and power element.

From the foregoing, it will be apparent that when power is applied to the shaft 21, 70 the crank arm 20 will cause the link 19 to move in the path of a circle, whereby at the highest movement of the crank arm 20, the link 19 will elevate the power end of the lever 14 to its greatest height, thus pushing 75 the knife block 5 downwardly to its limit against the supporting effect of the device B. In this movement, of course, the supplementary lever 15 participates, because of the link connection 17 of the latter with the 80 main lever 14. Since the reciprocating knife block 5 is approximately balanced by means of the device B, the same practically has no resistance to the operating instrumentalities, thus leaving the full power 85 thereof available for shearing the material placed between the jaws of the machine. This feature, together with the novel arrangement of levers and operating parts makes possible the utilization of a maximum 90 amount of shearing power with a minimum amount of operating power, thus effecting economy in operation and production.

Without further description, it is thought that the many features and advantages of the present invention will be readily apparent, and it will, of course, be understood, that various changes in the form, proportion, and minor details of construction may be resorted to without departing from the spirit 100 of the invention or scope of the appended claims.

I claim:

1. A shearing machine comprising a frame including a stationary knife block, a reciprocating knife block having one end working in a guide formed in the frame, a guide post slidably engaging with the reciprocating block at the end opposite the guide formed in the frame, means for operating said knife block comprising a main lever pivotally supported in said frame, power connections at one end of said main lever, a supplemental lever also pivotally supported in said frame, actuating plungers carried by the reciprocating knife block and connecting with the working end of said lever, and means for counterbalancing the weight of said reciprocating knife block located beneath the stationary knife-block 110 and projecting therethrough to engage with the reciprocating knife block.

2. A shearing machine including a stationary knife block, a reciprocating knife block, and means for operating said latter block comprising operatively connected levers having independent axes, means for connecting said levers with said reciprocating block, and means for counterbalancing the weight of the said reciprocating block 130

comprising supporting standards slidably mounted in the stationary knife block and having their upper ends in supporting engagement with the reciprocating block and 5 their lower ends connected with a weighted lever.

In testimony whereof I hereunto affix

my signature in the presence of two witnesses.

WALTER RACHALS.
